Patented Aug. 4, 1914

UNITED STATES PATENT OFFICE.

JOHN T. HAZELTON, OF SOMERVILLE, NEW JERSEY.

CARBURETER.

1,106,145.

Specification of Letters Patent.

Patented Aug. 4, 1914.

Application filed April 10, 1912. Serial No. 689,821.

To all whom it may concern:

Be it known that I, JOHN T. HAZELTON, a citizen of the United States, residing at Somerville, in the county of Somerset and State of New Jersey, have invented certain new and useful Improvements in Carbureters, of which the following is a specification.

My invention relates to improvements in carbureters for internal combustion engines, and is designed to improve the means by which the fuel in hydrocarbon and similar engines is vaporized.

The invention resides particularly in the devices for spraying the hydrocarbon and also in devices for mixing the required air therewith and commingling the gases as they pass to the ignition chamber.

These results are accomplished by the utilization of certain novel features of construction and combinations of parts as illustrated in the accompanying drawings wherein I have illustrated one complete example of the physical embodiment of my invention constructed according to the best mode I have so far devised for the practical application of the principles, and the device herein exemplified has proven highly satisfactory in actual practice.

Figure 1 is a sectional view of a carbureter embodying the invention. Fig. 2 is a horizontal sectional view on line 2—2 of Fig. 1. Fig. 3 is a horizontal sectional view on line 3—3 of Fig. 1, and Fig. 4 is a view of the throttle, detached.

In the preferred embodiment of the invention as herein illustrated the fuel is contained in the float chamber 1, as usual, the standard float 2, valve 3, and inlet 4, for fuel, being illustrated. The casing 5 which incloses the float chamber is provided with a central, conical tubular wall 6, open at the top, and communicating at its lower open end with an open chamber in the cylindrical extension 7. An inlet mouth 8 communicates with the chamber within the extension 7, for the admission of hot air, as usual.

The cylindrical upper structure 9 of the carbureter is cylindrical in cross section and provides a hot water or air space 10. An inlet and outlet are indicated by the numerals 11 and the space may be supplied with either of the elements therethrough. The cylinder 9 is also provided with an closed wall 12, which forms a passage way or duct communicating with and forming a

continuation of the conical shaped passage within the tubular wall 6 of the float chamber. This wall 12, as seen in Fig. 1 is corrugated, as at 13, to form ducts or elongated chambers in the fuel passage to aid in commingling the gases as they arise. And a further commingling of the gases is produced by the novel form of throttle valve 14 which is provided with pins 15 projecting therethrough and at each side thereof. The jacket 9 is provided with the usual air intake 16 and valve 17, and as these parts of the device are old and well known an extended description is unnecessary.

The vaporizer includes a needle valve 18 integral with the stem 19, which is threaded at 20 into a sleeve 21 that is in turn threaded into the bottom wall of the extension 7, and a clamp nut 22 holds the extension 7 in position. At its lower end the stem is provided with a hole 23 into which a tool may be inserted for turning the stem in the threaded sleeve to adjust the valve 18 in relation to its seat 24 formed at the upper end of the nozzle 25. A packing nut 26 closes the lower end of the sleeve 21 and is threaded thereon.

It will be seen that an ample space is provided within the nozzle 25 for fuel which is fed thereto from the fuel chamber through duct or passage 26 which leads to a horizontal passage 27 passing through the supporting lug 28 of the nozzle support 29. (See Fig. 2.) In addition to the vaporizing or spraying device formed between the needle valve 18 and the contracted end 24 of the nozzle 25, an extra jet of fuel is passed through the reduced extension 30 of the needle valve. As shown in dotted lines Fig. 1 a passage or duct 31 is drilled in the extension and opens within the nozzle at 32. A drip cup 23 is attached to the sleeve 21 within the extension 7 to catch the drip of fuel in priming.

In the operation of the carbureter fuel is admitted to the interior of the nozzle 25 and passes between the needle valve 18 and contracted nozzle end 24 from whence it emerges and is vaporized by the flow of hot air drawn in through the opening 8 and up through the conical tube 6. An additional jet of hydrocarbon is passed through the chambered extension of the valve, and at this point the vapor receives the additional supply of air through the auxiliary valve 17. As the gases for combustion pass upwardly through the pipe 12, they are broken up and commingled

by passing through the ducts formed by the corrugated wall of the pipe, and a further separation and commingling is occasioned by the rods or pins 15 in the throttle 14. In 5 this manner a thoroughly mixed fuel is supplied to the manifold of the engine.

From the above description taken in connection with the drawings it is believed the merits of my invention will be apparent, and 10 Having thus fully described my said invention, what I claim as new and desire to secure by Letters Patent is:—

1. In a carbureter, the combination with a nozzle having a contracted mouth and a fuel 15 supply, of a stem formed with a needle valve to co-act with said contracted mouth, and an extension on the end of said valve having a passage therethrough communicating with the interior of the nozzle and forming an 20 additional vaporizing jet.

2. In a carbureter, the combination with a nozzle having a contracted mouth and fuel supply, a threaded stationary sleeve forming a continuation of the nozzle and means for 25 securing the sleeve in the carbureter, of a stem threaded into said sleeve and provided with a needle valve, and an extension on said valve having a passage therein communicating with the interior of the nozzle and 30 forming a vaporizing jet.

3. In a carbureter the combination with a nozzle having a contracted mouth and a fuel supply, and a sleeve secured in the carbureter and having drip cup thereon, of a stem 35 threaded into said sleeve and provided with a needle valve to co-act with said contracted mouth, and an extension beyond said valve having a passage therethrough communicating with the interior of the nozzle and forming an additional vaporizing jet.

4. In a carbureter, the combination of a reservoir, a cover on the reservoir having a mixing tube extending transversely thereon and an air-inlet tube extending from the mixing tube through the reservoir, and 45 a fuel feed tube connected with the reservoir and having a nozzle supported in the air-inlet tube to discharge therein toward the mixing tube, with dual means in the air-inlet tube for controlling the discharge from the 50 nozzle, one of the means being adjustable for capacity and the other relatively smaller and constant in capacity.

In testimony whereof I affix my signature in presence of two witnesses.

JOHN T. HAZELTON.
